No. 855,748.

PATENTED JUNE 4, 1907.

H. F. BECHMAN.
PRINTING PRESS.
APPLICATION FILED AUG. 27, 1906.

THE NORRIS PETERS CO., WASHINGTON, D. C.

UNITED STATES PATENT OFFICE.

HENRY F. BECHMAN, OF BATTLE CREEK, MICHIGAN, ASSIGNOR TO DUPLEX PRINTING PRESS COMPANY, OF BATTLE CREEK, MICHIGAN.

PRINTING-PRESS.

No. 855,748.

Specification of Letters Patent.

Patented June 4, 1907.

Application filed August 27, 1906. Serial No. 332,170.

To all whom it may concern:

Be it known that I, HENRY F. BECHMAN, of Battle Creek, in the county of Calhoun and State of Michigan, have invented certain new and useful Improvements in Printing-Presses; and I hereby declare that the following is a full, clear, and exact description thereof, reference being had to the accompanying drawings, which form part of this specification.

This invention is an improvement in flat bed type printing web presses of the well known "duplex" type, such as disclosed in patent to Joseph L. Cox No. 478,503, dated July 5, 1892,—and the object of the present invention is to render such a press capable of printing any number of pages from two to sixteen, by twos; thus practically doubling the capacity of the duplex press by combining therewith suitable printing and web manipulating devices, and utilizing the web controlling mechanism of the old portion of the press to control the web manipulating portions of the new, and also utilizing the web reciprocating mechanism of the old press to actuate the additional impression cylinders.

The invention will be readily understood from the following description of the machine illustrated in the accompanying drawings, in which—

Figure 1 is a side elevation of a complete sixteen-page duplex press, and Fig. 2 is a diagrammatical longitudinal sectional view thereof.

The press contains two lower type beds 1 and 2, and two upper type beds 1^a and 2^a. The beds 1 and 2, are in substantially the same horizontal plane. The beds 1^a, 2^a are in substantially the same horizontal plane and superposed above the beds 1 and 2. The beds 1, 1^a are parallel, one over the other; and so are the beds 2, 2^a. All the beds are rigidly supported in the side frames of the press.

Co-acting with the beds 1, 1^a are cylinders 1^b, 1^c, and co-acting with type beds 2, 2^a are cylinders 2^b, 2^c. The cylinders 1^b, 1^c are journaled in cross heads 3, which are slidably mounted upon the side frames of the press, as in the duplex machine, and are reciprocated back and forth, so as to move the cylinders over the beds by means of pitman rods 3^a connected with crank wheels 3^b, as in the duplex machine. The cylinders 2^b, 2^c are similarly journaled in cross heads 3^e, also

slidably mounted on the sides of the main frame and connected to the cross heads 3, by rods 3^d, as shown, so that both sets of cylinders will be reciprocated simultaneously back and forth from the crank wheels 3^b. 60 These crank wheels are driven by gearing from the main shaft as is usual in the duplex presses.

Each pair of beds and cylinders is adapted to print a web of paper and can produce 65 eight printed newspaper pages from each web, from type forms placed on the bed, so that when the press is in full operation sixteen pages or less can be produced in multiples of twos, but when eight pages or less 70 are to be produced it is desirable to put one of the printing mechanisms out of operation.

A web *w'* may be led in over guides 4^a, through the feeding rolls 4^b, up over a looping roller 4^c, down under guide 4^d, in over a 75 guide 4^f, (traveling with cylinder 1^b), then between bed 1 and cylinder 1^b, then up over roller 4ⁱ, (traveling with cylinder 1^b), under and over rollers 4^g and 4^h to roller 4ⁱ, (traveling with cylinder 1^c), down between cylinder 1^c and bed 1^a, up over guide 4^j, (traveling with cylinder 1^c), to and over guide 4^k, down under a second looping roller 4^l; and up to the delivering mechanism 4^m where the web is split; then down under guide 4ⁿ, and 85 one-half of it passes over turner 4^o and guides 4^p, 4^q, to the folding mechanism F, while the other half passes direct over roll 4^r to the folder, the two halves of the web being superposed and assembled at the 90 folder, as is usual in the duplex presses. The feeding-in rolls 4^b and the delivery mechanism 4^m are constructed and operated as in the ordinary duplex press and need no detailed description herein. So are the looping rollers 4^c, 4ⁱ which are mounted on reciprocating bars 5 actuated by lever 5^a, operated by a cam 5^c on a shaft 5^d, as usual in the duplex presses. 95

A web of paper *w'* may be led in, from a 100 roll W² at the opposite end of the press, under a guide 6^a, through feeding-in mechanism 6^b, (similar to 4^b) then over looping roller 6^c, (similar to 4^c) down under a guide 6^d to and over cylinder guide 6^e, then between 105 bed 2 and cylinder 2^b, up over cylinder guide 6^f to, under and over guides 6^g, 6^h, back over cylinder guide 6ⁱ, down between bed 2^a and cylinder 2^c, up over cylinder guide 6^j to guide 6^k, then to the second looping roller 6^l 110

(similar to 4¹) then up to delivering mechanism 6^m (similar to the delivering mechanism 4^m) and thence passes to guide 6ⁿ where it is split and one-half the web passes over turner 5 6°, and guide 6^q to the folder F, and the other half of the web passes over guide 6^r to the folder; the two parts of the web w² being superposed and assembled on the former with the two halves of the web w', so that the 10 products of both presses are assembled at the folder and delivered as one paper.

The feeding devices 6^b, are driven in unison with the feeding devices 4^b by means of a train of gears 6^s driven by a bevel gear 6^t meshing with a bevel gear 7^a, on a counter-shaft 7, which is driven by a bevel gear 7^b, meshing with a bevel gear 5^e, driven by gear 15 5^f, and meshing with gear 5^g on shaft 5^d.

The delivery mechanism 6^m is driven in 20 unison with the feed and with the delivery mechanism 4^m by means of a train of gears 6^p driven from the gear 6^s, as indicated in Fig. 1, of the drawings. Any other suitable 25 gearing may be adopted for driving the feeding and delivery mechanism of the press in unison. The shaft 7 may be made in sections and provided with a coupling member 7^c and by properly shifting this coupling the 30 feed and delivery mechanism 6^b, 6^m for the web w² can be put out of operation.

The looping rollers 6^c, 6^f are mounted on a bar 8, corresponding to bar 5, and are operated from bar 5, by means of bell-crank levers 8^a, 5^k and connecting rod 8^b. One arm 35 of lever 5^k is connected with bar 5, and the short arm is connected by link 8^b to the short arm of lever 8^a, the long arm of which is connected to bar 8. Consequently the two sets of looping rollers 4^c, 4^l, and 6^c, 6^f 40 will be operated in unison by and from the one set of controlling cams 5^c. The link 8^b may have its end engaging lever 5^k hooked as at 8^c, so that it can be detached from the lever 5^k if it should be desired to throw the 45 looping mechanism 6^c, 6^f out of operation, as would be desirable if the feeding mechanism 6^b and delivery mechanism 6^m were out of operation, or no web was being printed on the beds 2, 2^a. Any other disconnectible 50 connections between the two sets of web manipulating devices might be employed, and where only eight pages or less are to be printed, it might be desired to cut one set of cylinders out of operation and for this purpose the connecting rod 3^d might be detached from the cross head 3, in any suitable 55 manner.

When the press is threaded as shown in Fig 2, of the drawings, any number of pages over 60 eight and up to sixteen can be produced by using a full width web w', and a two, four, six, or eight page web w². The machine can also be used to print one web in multi-color if desired, in which case, for example, the 65 web w² might be stripped from the machine

and the web w' after being printed on one side by bed 1 and cylinder 1^b, is carried directly on to and between bed 2, and cylinder 2^b, following the course of web w² until it reaches the guide 6^k and then it may be passed on to 70 the delivery 6^m, or across and between the bed 1^a and cylinder 1^c, and thence to the delivery 4^m. In the first instance it could receive a black color from bed 1, and a multi-color on bed 2, on the same side of the web, 75 and be perfected in black on 2^a. In the second case it could be printed in black on bed 1, in another color on the same side on bed 2, another color on the opposite side on bed 2^a, and be perfected in black on bed 1^a. If desired the web could be passed through the feed rolls 6^b between the beds 1 and 2, and could be passed over the looping mechanisms 80 6^c, 6^f between the printing mechanisms. It will be obvious that the press can be threaded to print and perfect one web in color in various ways and it can also be threaded to print upon one side of the web only.

The feature of the present invention is the provision of four beds and four cylinders, and 90 two feeding and two delivery mechanisms operated synchronously and from the same controlling means whereby any desired number of pages up to sixteen can be printed in one color and eight or less pages can be printed in multi-color.

Having described my invention what I claim as new and desire to secure by Letters Patent is:

1. In a printing press, the combination of 100 the side frames, a pair of beds therein arranged end to end in substantially the same plane, a second pair of beds arranged parallel with and substantially in a plane above that of the first beds, impression cylinders co-acting 105 with the beds, a web feeding mechanism at one end of the press, a second web feeding mechanism intermediate the pairs of beds, a web looping mechanism, web delivering mechanism, web guides for directing webs through the press, a folder, and means for directing the webs from the delivery mechanism to the folder.

2. In a flat-bed-web-printing press, the combination of two type beds in substantially the same plane, two additional type beds in a plane above and parallel with that of the first type beds, an impression cylinder co-acting with each type bed, means for reciprocating said cylinders, web feeding, looping and delivering mechanism at the outer end of the first pair of type beds, a similar set of web feeding, looping and delivering mechanism intermediate the pairs of type beds; and web guides whereby webs may be directed 120 between the beds and cylinders to be printed thereby.

3. In a printing press, the combination of the side frames, a pair of beds therein arranged end to end in substantially the same 130

plane, a second pair of beds arranged parallel with and above the first beds, impression cylinders co-acting with the beds, a web feeding mechanism at one end of the press, a second web feeding mechanism intermediate the pairs of beds, a web looping mechanism adjacent each feeding mechanism, web delivering mechanism, web guides for directing webs through the press, a folder, and means 5 for directing the webs from the delivery mechanism to the folder.

4. In a flat-bed-web printing press, the combination of two adjacent type beds in substantially the same plane, two additional 15 type beds above and parallel with the first type beds, an impression cylinder co-acting with each type bed, means for reciprocating said cylinders, web feeding, looping and delivering mechanism at the outer end of the 20 first pair of type beds, a similar set of web feeding, looping and delivering mechanism intermediate the pairs of type beds; and web guides whereby webs may be directed between the beds and cylinders to be printed 25 thereby.

5. In a printing press, the combination of two perfecting mechanisms, each comprising two stationary type beds arranged parallel one above the other, an impression cylinder 30 co-acting with each type bed, means for reciprocating the cylinders over the beds, guides for directing a web of paper between the beds and cylinders, web feeding and delivering mechanism for each pair of beds and cylinders, one set of such mechanism being arranged at the end of the press and the other being arranged intermediate the pairs of beds; a looping mechanism adjacent each feed and delivery mechanism, a cam and 35 connections for operating one looping mechanism, and means for operating the second looping mechanism from the first; a folder at the end of the press, and guides for directing webs of paper from the delivery mechanisms 40 to the folder.

6. In a printing press, the combination of the side frames, a pair of beds therein arranged end to end in substantially the same plane, a second pair of beds arranged parallel with and above the first beds, an impression cylinder co-acting with each bed, a web feeding mechanism at one end of the press, a second web feeding mechanism intermediate the pairs of beds, gearing between 50 the said feeding mechanisms whereby they are driven in unison, a web looping mechanism for each feeding mechanism, a cam for operating all the looping mechanisms in unison, web delivering mechanism adjacent each looping mechanism, means for operating the web delivery mechanisms in unison, guides for directing webs through the press, a folder, and means for directing webs from the delivery mechanisms to the folder.

65 7. In a flat-bed-printing press, the com-

bination of two adjacent type beds arranged in substantially the same plane, two additional type beds above and parallel with the first type beds, an impression cylinder co-acting with each type bed, means for reciprocating 70 said cylinders, a web feeding, looping and delivering mechanism at the outer end of the first pair of type beds, a similar set of web feeding, looping and delivering mechanism intermediate the pairs of type beds, and connections whereby said web feeding, looping and delivering mechanisms are operated in unison; means for throwing one set of web feeding, looping and delivering mechanism out of operation, and web 75 guides whereby webs may be directed between the beds and cylinders to be printed thereby.

8. In a printing press, the combination of two perfecting mechanisms, each comprising 80 two stationary type beds arranged parallel, one over the other, an impression cylinder co-acting with each type bed, means for reciprocating the cylinders over the bed, guides for directing a web or webs of paper between 85 the beds and cylinders, web feeding and delivering mechanism for each pair of beds and cylinders, one set of said mechanism being arranged at the end of the press and the other being arranged intermediate the pairs of beds, 90 a looping mechanism adjacent each feed and delivery mechanism, a cam and connections for operating one looping mechanism, and connections for operating the second looping mechanism from the first.

9. In a printing press, the combination of two perfecting mechanisms, each comprising two stationary type beds arranged parallel one over the other, an impression cylinder co-acting with each bed, means for reciprocating 105 the cylinders over the beds, guides for directing a web or webs of paper between the beds and cylinders, web feeding and delivering mechanism for each pair of beds and cylinders, one set of such mechanism being arranged at the end of the press and the other set being arranged intermediate the pairs of beds, a looping mechanism adjacent each feed and delivery mechanism, a cam and connections for operating one looping mechanism, and connections for operating the second looping mechanism from the first; a folder at the end of the press, guides for directing a web or webs of paper from the delivery mechanisms to the folder, and means 110 whereby one set of cylinders and its relative feeding, looping and delivering mechanisms may be put out of operation.

In testimony that I claim the foregoing as my own, I affix my signature in presence of 115 two witnesses.

HENRY F. BECHMAN.

In presence of—

F. W. DUNNING,
